UNITED STATES PATENT OFFICE.

WYATT R. R. FRYE, OF WASHINGTON, DISTRICT OF COLUMBIA.

PHOTOGRAPHIC-PRINTING APPARATUS.

Application filed July 16, 1919. Serial No. 311,286.

To all whom it may concern:

Be it known that I, WYATT RICHARD R. FRYE, a citizen of the United States, residing at Washington, in the District of Columbia, have invented certain new and useful Improvements in Photographic-Printing Apparatus, of which the following is a specification.

This invention relates to apparatus for printing from photographic negatives and means for timing such printing and has for its object to provide a device embodying new and improved means, and the features of convenience, accuracy and speed of operation.

With these and other objects in view the device comprises certain novel combinations and arrangements of parts as will be hereinafter more fully described and claimed.

Referring to the accompanying drawings which are made a part hereof, and on which similar reference characters indicate similar parts,

Figure 1 is a view of the device in front elevation, certain parts being broken away to show mechanical features,

Figure 2 is a sectional view taken on line 2-2 of Figure 1.

Figure 3 is a view in front elevation of the timing mechanism set ready for initiating operation,

Figure 4 is a transverse sectional view through the timing mechanism as indicated by line 4-4 of Figure 3,

Figure 5 is a perspective view of the light box showing one of the various replaceable and interchangeable glass plates employed therein,

Figure 6 is a perspective view of the device for hinging the print clamping mechanism,

Figure 7 is a view in side elevation of the clutch for connecting and disconnecting the timing mechanism with and from the printing mechanism,

Figure 8 is a view in edge elevation of the clutch shown at Figure 7, parts being broken away to show the bolt,

Figure 9 is a detail enlarged view of the adjustment of the pedal to the link,

Figure 10 is a diagrammatic view of the wiring of the electrical system.

The improved printing device which forms the subject matter of this application,

is for use in printing from photographic 55 negatives, either plates or films. It comprises a table 15 over an aperture in which a glass plate 16 is located which may be the negative itself, if the negative is a plate, or may be a clear glass plate upon which the 60 film is placed, in case of a film negative. Upon this glass plate the paper to carry the print is disposed with the sensitive side downwardly. To maintain the paper in proper position upon the plate hinged members 17 and 18 are employed. The member 17 is hinged to the member 18 which in turn is hinged to a block 19 carried on the table 15. The manner of hinging to this block is important, the hinge itself being shown in 70 perspective at Figure 6 and comprises a leaf 20 fixedly secured to the block 19 with a leaf 21 hinged thereto upon the pintle 22. The leaf 21 is held yieldingly upon the block 19 by a spring 23. The leaf 21 is provided with 75 an upturned flange 24 abutting a similar flange 25 upon a leaf 26 of a hinge connected with the hinged member 18 by the leaf 27 pivoted to the leaf 26 by the pintle 28.

The two flanges 24 and 25 are pivotally 80 connected together by means of the pivot pin 29 and limited oscillation upon such pivot is provided for by means of the rivets 20 engaging within slots in such flanges. By means of this oscillation and the spring 23 85 provision is made for any unevenness of the device or the use of the device upon film negatives or plate negatives.

Erected also upon the block 19 are ears 31 to which are pivoted arms 32. The arms 32 are fixedly secured to the pintle 33 to which is also fixed the arm 34 connecting by means of a link 35 with the pedal 36. The connecting means between the link 35 and the pedal 36 comprises an arm 37 rigidly secured to the shaft 38 to which is also secured the arm 39. The arm 39 is connected by a link 40 with a lever 41 which in turn is connected with the pedal 36 by the link 42. For the purpose of maintaining the pedal 100 normally and yieldingly in raised position a spring 43 is employed connected with the lever 41 by means of a link 44.

The shaft 38 also carries an arm 49 pivotally connected to the link 50 which in turn is pivotally 105 connected with the sliding bar 51 carrying a contact member 52 in position to engage a fixed contact member 53 all so arranged that

when the pedal 36 is depressed the bar 51 is likewise depressed bringing the contact member 52 into electrical contact with the contact member 53 for the purpose of energizing lights employed for printing purposes. To hold the bar 51 with the contacts 52 and 53 normally yieldingly spaced, a spring 53 is employed with the necessary brackets and the like for lending efficiency 10 to such spring.

The arms 32 which are actuated by the pedal 36 and connecting parts extend through slotted rods 55 and 56 the former carried rigidly by the hinged section 17 and 15 the latter by the hinged section 18. The arms 32 bear directly upon washers 57 which in turn bear upon springs 58 so that the tension of the arms 32 upon the hinged members 17 and 18 is a yielding tension. When 20 the arms 32 are lifted to the position 32' the hinged members are also lifted to dotted line position as shown at Figure 2 whereby the print or negative or both may be removed for replacing with other like negatives or paper for printing.

For printing, a plurality of lights, preferably electric lights, and still more preferably, incandescent electric lights, are provided located in the box 59. The box 59 is 30 slidably located under the table 15 by providing cleats 60 thereon, and may be covered by any light-transmitting or transusing device or plate indicated at 61, such plate or device being when desired interposed between the lights and the negative being printed from. The lights themselves are indicated diagrammatically at Figure 10 and will be hereinafter more fully described in regard to their circuits.

40 For the purpose of exposing the negative a predetermined interval of time, a timing mechanism is employed capable of being set to extinguish the lights at any predetermined length of time after the lights

45 are lighted by the depression of the pedal 36. The timing mechanism is located at any approved point relative to the table 15 and may be upon a shelf or brace 62 supported beneath the table top 15 by the legs

50 63, although the exact location of the device is immaterial to the present invention. The timing mechanism comprises an organized mechanism shown at Figures 3 and 4 and in the location referred to at Figure 1.

55 It comprises a base 64 secured to the supporting structure and carrying two or more guide rods 65 spaced parallel above the base 64 in any approved manner, as by the uprights 66 and 67. Upon these guide rods

60 65 a carriage indicated in its entirety at 68 is slidably mounted and is held yieldingly in its position adjacent its supporting member 67 by means of a flexible band 69 wound about a tension drum 70 and passing over 65 a pulley or roller 71. Mounted also upon

the structure is a constantly traveling member 72, here shown conventionally in the form of a sprocket chain it being understood that any moving member may be employed instead of a sprocket chain. With 70 a sprocket chain employed such chain passes over sprockets 73 and 74, the latter of which is constantly driven in any approved manner, as by the motor 75, which is connected to transmit power to the shaft 76 75 by the use of any usual and ordinary gearing, as for instance, the worm 77 engaging the gear 78 carried rigidly with the pinion 79 which in turn engages the gear 80 upon the shaft 76. The sprocket 80 chain 72 therefore while the motor is energized is driven at a pre-determined speed. It is only necessary to connect and disconnect the carriage 68 with such moving member for a pre-determined space of travel to 85 provide for timing. The connection with the travelling member 72 is accomplished by means of jaws 81 and 82, the former of which is fixed to the carriage 68 and the latter vertically slidable with a spring 83 90 tending to hold the jaws yieldingly apart. For closing the jaws into engagement with the travelling member 72 a lever 84 is hinged at 85 and connected with the sliding jaw 82 by means of a link 86. It is obvious 95 therefore that when the lever 84 has been depressed from the position shown at Figure 3 to the position shown at Figure 4, the sliding jaw 82 will be moved into clamping engagement with the travelling member 100 72 and will travel therewith until released. To maintain the clamping jaw in such clamping engagement the jaw member 82 carries a spring depressed detent 87 which engages under a rail 88 mounted to slide 105 in the guideways 89 carried rigidly upon the structure. The rail 88 terminates in its overhang portion at the point indicated as 90 in Figure 3, it being understood that this point is variable according to the position of the sliding rail 88. As the carriage 68 moves with the traveling member 72 indicated by the arrow, the jaws are maintained in clamping position until the detent 87 has moved beyond the point 90 110 115 of the rail 88 when there being no longer any mechanism for maintaining the jaws in closed position, the jaws are separated by the spring 83. The lever 84 also carries an electric switch 91 which is held in closed 120 position when the lever is depressed and opens when the lever rises under the action of the spring 83 which will be perfectly obvious from Figure 4. When therefore the timing mechanism has passed beyond the extremity of the sliding rail 88 so that it is released from the traveling member 72, two things occur in the opening of the jaw, one being the opening of the switch 91 for the purpose hereinafter ex- 125 130

plained, the other being the releasing of the carriage from the travelling member 72 permitting its immediate and automatic return to engagement with the supporting member 67 under tension from the drum 70.

To depress the lever 84 on the carriage 68 a bar 92 is slidably mounted upon the support 67 and provided with a detent 93 adapted to engage the lever 84 when the bar 92 descends and to pass by such lever unobstructedly when the bar ascends. To hold the bar 92 at its upper limit a spring 94 is provided. To actuate the bar 92 a link 95 is pivotally connected with the bar 51 at one end and at its opposite end with the arm 96 upon the shaft 97. The shaft 97 carries a second arm 98 which is connected by means of a link 99 with an arm 100 carried upon the shaft 101. The shaft 101 carries an arm shown in its entirety at 102, which in turn is pivotally connected with a link 103 pivoted to the bar 92 at 104. The component arm 102 is employed as a clutch between the printing mechanism and the timing mechanism. This component arm 102 comprises a member 105 rigidly attached to the shaft 101 while the main arm 102' which is pivoted to the link 103 is free to rotate upon the shaft 101. The arm 105 carries a spring pressed bolt 106 adapted to engage a socket 107 in arm 102' and by reason of the pin 108 fixed laterally in said bolt to hold the bolt out of engagement with the socket when the bolt has been lifted against the tension of its spring and rotated a part of a revolution so that the pin 108 bears upon the surface of the arm 105.

For the purpose of adjusting the bar 88 conveniently a gear 109 is mounted in engagement with the rack face 110 of such bar 108 and is provided with a shaft 111 which extends upwardly from such gear and cooperates with an indicator 112 mounted upon the top of the table 15. By turning the indicator to any desired or pre-determined position the rotation of the shaft 111 and its connected gear 109 slides the bar 88 upon its supporting guide 89 so that the point 90 is at any desired or pre-determined position longitudinal of the timing device, whereby the hooked detent 87 slips off from engagement with such bar after any pre-determined length of travel.

For the purpose of adjusting the relation of the pedal 36 to the link 42 for use by persons of different height or by reason of the adjustment of the link 42 upon the lever 41, or for any other purpose, means is provided for accommodating the pedal at various heights upon such link. This is shown in enlarged detail at Figure 9. It comprises a block 113 pivotally secured to the arm of the pedal 36 as at 114 and provided with a recess for the passage therethrough of the link 42 which is provided with a rack formed

in its edge as indicated at 115. Within the block 113 a lug 116 is located in position to engage with the rack 115 when such rack is at one limit of its movement within the block 113. To move and maintain the rack 70 in such position a detent 117 is employed, pivoted at 118 in the block 113 and provided with a spring 119 and a lever 120 for actuation and manipulation in an obvious manner.

For actuating the motor 75 and the lights within the box 59 an electric circuit or system of wiring is employed wherein a plurality of lights 122, 123, 124, 125, 126, 127, and 128 are employed, it being understood 75 that the number of lights here indicated as seven is immaterial to the present invention, the requisite being sufficient actinic action upon the printing paper. The light 122 is indicated as a red light or pilot light or light 80 simply for properly positioning the paper without being acted upon, the actinic rays being interrupted by the red glass. This red light 122 is connected directly to the main line circuit 129 and 130 and is lighted 85 at all times when there is any current in the system which is provided from any approved source of electric energy indicated at 131 with a master switch 132 for controlling the entire system. When, therefore, the 90 master switch is closed the red light 122 is lighted, and the other switches individually manipulated, as for instance, the switch 133 for controlling the motor 75 and the switches 134, 135, 136, 137, 138, and 139 for controlling 95 respectively the lamps 123 to 128 inclusive. The action of the switches 52 and 91 has already been described in conjunction with the appropriate mechanism hereinbefore described, an additional switch 140 being provided whereby switch 52 or 91 may be thrown into and out of circuit so that when the timing mechanism is being used the switch 52 will be inoperative and when the timing mechanism is not used the switch 91 100 will be inoperative.

Preferably the lamps 122 to 128 inclusive will be located in the box 59 with appropriate flexible connection so that the box 59 may be slidably inserted and withdrawn 115 as a drawer and with the switches 134 to 140 also appropriately located, preferably, though not necessarily, upon the box, or if found convenient, upon any part of the structure, the location being wholly immaterial to the present invention and wholly within the skill of an electrician.

In operation it will be understood that the master switch 132 and the switch 133 are appropriately closed whereby the motor 75 120 is energized. Such of the lamps 123 to 128 as are found necessary for the printing of the exposed paper will be selected and their respective switches closed and the adjustable bar 88 moved by the rotation of the shaft 130

11 so that the carriage 68 shall travel a desired distance along the guides 65 before being released by passing from the point 90 of the bar 88. The mechanism having been 5 set at these required adjustments, the hinged members 17 and 18 are lifted to dotted line position (Figure 2), the required negative and printing paper are placed in position, the pedal actuated by the foot to clamp the 10 hinged members 17 and 18 down to full line position upon the print. Depression of the pedal 36 closes the switch 52 or the switch 91 whereby the lights prearranged by the closing of their several individual switches 15 are simultaneously energized and the carriage 68 clamped to the traveling member 72. The device continues to retain the paper in printing position over the negative and in position to be acted upon by the underlying 20 lights until the travel of the carriage along the bar 88 releases the jaws 81 and 82, which opens the switch 91. The carriage returns then under the impetus of the tension drum 70 and the actuation of the pedal 36 opens 25 the hinged members to release the printed paper and the negative, if it is to be replaced. The device is now in position for the next cycle of operation which corresponds identically with the foregoing cycle.

30 Having thus fully described my said invention, what I claim as new and desire to secure by Letters Patent, is:

1. In a photographic printing apparatus the combination with an apertured table 35 members hingedly connected with the table and adapted to cover the aperture, slotted uprights carried by the hinged members, springs surrounding the slotted uprights, a lever inserted through the slits of the up- 40 rights and bearing upon the springs, a pedal, and means connecting the pedal with the lever whereby depression of the pedal clamps the hinged members over the aperture.

45 2. In a photographic printing apparatus the combination with an apertured table of members hingedly connected and proportioned to cover the aperture of the table, a hinged leaf connected to one of said hinged 50 members and provided with an up-turned flange, a member secured to the table and provided with a co-acting and abutting up-turned flange, a pivot connecting the two flanges permitting oscillation of the one relative to the other, and means for limiting the oscillatory movement of the one flange relative to the other.

60 3. In a photographic printing apparatus the combination with an apertured table, of members hingedly connected adapted to cover the aperture of the table, a hinged leaf connected to and extending beyond one of the hinged members and provided with an up-turned flange, a member hingedly and 65 yieldingly connected with the table and pro-

vided with an up-turned flange abutting the up-turned flange of the hinged leaf, a pivot pin connecting the two flanges permitting oscillation of one relative to the other, and means for limiting the oscillatory move- 70

75 4. In a photographic printing apparatus the combination with an apertured table of members hingedly connected and adapted to cover the aperture, a hinged leaf connected with one of the members and provided with an up-turned flange, a member hingedly connected with the table and provided with an up-turned flange abutting the up-turned flange of the hinged leaf, a pivot pin connecting the up-turned flange to permit oscillatory movement, means to limit the oscillation, uprights carried by the hinged members, a lever operating in conjunction with the uprights, springs interposed between the 80 levers and hinged members, a pedal, and means connecting the pedal with the lever whereby the depression of the pedal clamps the hinged members over the aperture.

85 5. A photographic printing apparatus comprising an apertured table, electric lights disposed beneath the table, an electric circuit controlling the lights, hinged members 90 for clamping a negative and a sheet of paper in printing position, a pedal for simultaneously actuating the hinged members and closing the circuit, and adjustable timing means for automatically breaking the circuit at a predetermined time independently of the clamping means, substantially as set 95 forth.

100 6. A photographic printing apparatus comprising an apertured table, members hingedly connected adapted to cover the aperture of the table, a pedal pivotally connected to the table, means connecting the hinged covering members and the pedal comprising a collar pivoted to the pedal, a link extending through the collar and slidably adjustable therein and means for locking the 105 link to the collar in adjusted position.

110 7. A photographic printing apparatus comprising an apertured table, an electric lamp beneath the aperture, means for clamping a negative and a sheet of paper in printing position above the aperture, a circuit for said lamp, a pedal for simultaneously and positively actuating said clamping means and closing the circuit, and an adjustable timing means comprising a reciprocating 115 carriage for breaking said circuit at a predetermined time, substantially as set forth.

120 8. A photographic printing apparatus comprising an apertured table, members hingedly connected adapted to cover the 125 aperture of the table, a pedal pivotally connected to the table, a collar pivoted to the pedal and provided with an inwardly extending lug, a notched link within the collar and providing a connection between the 130

pedal and the hinged members, said link having its notches adapted to selectively engage the lug on the said collar.

9. A photographic printing apparatus comprising an apertured table, members hingedly connected adapted to cover the aperture of the table, a pedal pivotally connected to the table, a collar pivoted to the pedal and provided with an inwardly extending lug, a notched link within the collar and providing a connection between the pedal and the hinged members, said link having its notches adapted to selectively engage the lug on the said collar and a lever pivoted to the collar adapted to hold the collar and notched link in selective contact.
10. A photographic printing apparatus comprising an apertured table, members hingedly connected adapted to cover the aperture of the table, a pedal pivotally connected to the table, a collar pivoted to the pedal and provided with an inwardly extending lug, a notched link within the collar and providing a connection between the pedal and the hinged members, said link having its notches adapted to selectively engage the lug on the said collar and means for holding the collar and notched link in selective contact.
11. In a photographic printing apparatus, a table having an aperture, clamping means hinged to the table at one side of the aperture and adapted to hold a negative and a sheet of paper in printing position, an electric lamp under the table, a pedal connected to operate said clamping device, a switch in circuit with said lamp, connections from said switch to said pedal whereby said lamp is lit as the clamping device is operated and vice versa, means to hold the pedal down, means for automatically releas-

ing it, and means comprising a motor operated endless chain carrying a carriage for adjusting the length of time it remains in depressed position, substantially as set forth. 45

12. In a photographic printing device, a table having an aperture, an electric lamp beneath the aperture, means adapted to hold a negative and a sheet of paper, and movable into and out of printing position over the aperture, a pedal under the table adapted to be depressed to move said clamping means into printing position, a circuit closing element adapted to be simultaneously moved by said pedal, means to hold the pedal in depressed position, adjustable motor operated means to automatically release said pedal, and a spring to restore the pedal and connected parts to normal position, substantially as set forth. 60

13. In a photographic printing device, a table having an aperture, an electric lamp beneath the aperture, means adapted to hold a negative and a sheet of paper, and movable into and out of printing position over the aperture, an electric circuit for said lamp, an adjustable timing switch in said circuit, a manually operated device connected to said holding means and to an element of said timing switch whereby the circuit is closed as the holding means approaches printing position, and means also connected to the manually operated device whereby the circuit may be closed independently of said timing switch, substantially as set forth. 65

In witness whereof, I have hereunto set my hand and seal at Washington, District of Columbia this 16th day of July, A. D. nineteen hundred and nineteen.

WYATT R. R. FRYE. [L.S.]

Witness:

E. W. BRADFORD.
